(57) **CLAIM**

I claim the ornamental design for an inflator, as shown and described.

DESCRIPTION

FIG. 1 is a front perspective view of an inflator in accordance with the present invention

FIG. 2 is a left side view of the inflator of FIG. 1.

FIG. 3 is a right side view of the inflator of FIG. 1.

FIG. 4 is a front view of the inflator of FIG. 1.

FIG. 5 is a rear view of the inflator of FIG. 1.

FIG. 6 is a top view of the inflator of FIG. 1; and,

FIG. 7 is a bottom view of the inflator of FIG. 1.

The portions of the inflator shown in broken lines are included for the purpose of illustrating environment and form no part of the claimed design.

1 Claim, 7 Drawing Sheets
